UNITED STATES PATENT OFFICE.

ANTOINE EMILE VEZINA, OF MONTREAL, QUEBEC, CANADA.

FURNACE-DOOR AND OPERATING MEANS THEREFOR.

1,209,082.

Specification of Letters Patent. Patented Dec. 19, 1916.

Application filed April 14, 1913, Serial No. 761,011. Renewed May 15, 1916. Serial No. 97,731.

To all whom it may concern:

Be it known that I, ANTOINE EMILE VEZINA, a subject of the King of Great Britain, and a resident of the city of 5 Montreal, in the Province of Quebec, in the Dominion of Canada, have invented certain new and useful Improvements in Furnace-Doors and Operating Means Therefor; and I do hereby declare that the following is a 10 full, clear, and exact description of the same.

The invention relates to improvements in furnace doors and operating means therefor, as described in the present specification 15 and illustrated in the accompanying drawings that form part of the same.

The invention consists essentially in the novel construction and arrangement of parts whereby a rolling slide door of peculiar form is operated by foot power by 20 means of a suitable gear mechanism.

The objects of the invention are to devise a door that will relieve the attendant from much of the danger and trouble incident to 25 the care of a furnace, to minimize the length of the period that the furnace door is open during the time of firing up, to facilitate the operation of sliding doors and generally to provide a simple, cheap and durable construction for the aforesaid purpose.

In the drawings, Figure 1 is a front view of the furnace doors and operating mechanism showing one set of slats partly broken away. Fig. 2 is a plan view from the top. 35 Fig. 3 is an end view of the door, casting and mechanism showing parts of the device in vertical section.

Like numerals of reference indicate corresponding parts in each figure.

40 Referring to the drawings, 1 are horizontal plates mounted on the winding posts 2 adjacent to each end thereof and having the arc-shaped slots 3 made in the corners thereof and forming, with said post, reels 45 having four flat sides 4. 5 is a casting having the central oval opening 6 therethrough, the flanges 7 and 8 extending outwardly therefrom forming bearings for the winding posts 2 and the lugs 9 from the rear side. 50 10 are slats having the outwardly extending flanges 11 at the top and bottom thereof forming hinge members. 12 are rods forming the pin members of the hinges and joining said plates together in two sets for 55 double doors to close said opening 6. The

outer end slats are hinged to the said winding posts and the plates 1 engage the slats so that said slats roll around said reels and form rolling and sliding doors.

13 are guides extending across the upper 60 and lower ends of the slats 10 and guiding said slats over the opening 6.

14 are guards extending in curves forwardly at each end of the casting 5 adjacent to the upper plates 1. 65

15 are bearings secured to the head wall of the furnace below the casting 5 or forming part therewith.

16 is a horizontal crank shaft journaled in the bearings 15. 70

17 is a crank lever mounted on the crank shaft 16 intermediate of the length thereof.

18 is a pedal arm mounted in the bearing 19 supported on the floor of the furnace room. 75

20 is a pedal at the upper end of the pedal arm.

21 is a connecting rod joining the crank lever 17 to the pedal arm 18 intermediate of the length of the latter. 80

22 is a spiral spring encircling the shaft 16, one end being attached to the bearing 15 and the other end to the shaft and winding up tightly on said shaft on the operation of the pedal 20, thus insuring the reverse direction of rotation of said shaft on the release of said pedal. 85

23 are bevel gears mounted at the lower end of the winding post 2.

24 are segmental bevel gears mounted at 90 the ends of the shaft 16 and coacting with the bevel gears 23 on the rotation of the shaft 16.

It will be seen that the operation of this invention is very simple indeed, as the double door is kept normally closed and in this position the spring 22 is only slightly in tension, so there is a minimum continuous strain on the said spring. 95

In order to open the doors to fire up the attendant presses his foot on the pedal, which rotates the crank shaft and as the segmental gears coact with the other gears, the reels or winding posts will be rapidly rotated, thus drawing the sets of slats apart 100 and winding each set on a reel. The moment the pressure on the pedal is released the spring 22 reverses the direction of rotation of the shaft 16, which reverses the direction of rotation of said winding posts 110

and unreels the slats, which are guided over the fire box door opening by the guides 13, until they meet in the center.

What I claim is:—

- 5 1. In furnace doors and operating means therefor, a frame secured to the head of the furnace having bearings projecting outwardly therefrom at each corner thereof, posts journaled in said bearings, plates
  - 10 mounted on said posts adjacent to said bearings, slat doors winding on said plates, gears mounted on the lower ends of said posts, a spring held horizontal shaft journaled in suitable bearings supported at the
  - 15 lower end of said frame, a crank mounted on said horizontal shaft, a pedal, a connecting rod from said pedal to said crank, and segmental gears mounted on said horizontal shaft and coacting with said gears.
  - 20 2. A furnace door and operating means therefor, comprising, a frame having outstanding lugs at the upper and lower corners forming post bearings and downwardly extending lugs at the lower end forming
  - 25 shaft bearings, posts journaled in said post bearings, a shaft journaled in said shaft bearings, a spiral spring encircling said shaft and attached thereto and to a lug, a crank fixedly mounted on said shaft, a
  - 30 pedal suitably connected with said crank, a pair of bevel gears, one mounted on each post at the lower end, coacting gears mounted on said shaft, and a plurality of slats hinged together in two sections respectively
  - 35 and adapted to be wound around the posts on the pressure of said pedal.
3. A furnace door and operating means

therefor, comprising, a rectangular frame having lugs extending inwardly therefrom, lugs extending outwardly therefrom at the upper and lower corners forming shaft bearings, brackets depending from the lower corners forming shaft bearings and gear frames, and curved guides extending laterally and forwardly from the top of the sides, posts journaled in said post bearings, a shaft journaled in said shaft bearings and spring held in its normal position, gears mounted at the lower end of said posts, co-acting gears mounted on said shaft, a pedal operatively connected with said shaft, and slats vertically arranged and hinged together in two sections respectively.

4. A furnace door and operating means therefor, comprising a plurality of slats each having outwardly extending flanges at the top and bottom thereof, rods pivotally secured in said flanges adjacent to the ends thereof and joining said slats together in two sections and forming double doors, a frame having guides for sliding said slats and bearings at the ends, winding posts journaled in said bearings, plates mounted toward the upper and lower ends of said posts and having their corners slotted to receive said rods, and means for operating said posts.

Signed at the city of Montreal, Province of Quebec, Canada, this 27th day of February, 1913.

ANTOINE EMILE VEZINA.
